ERNST GEIGER, OF IRVINGTON, NEW JERSEY

MECHANICAL PARKING GARAGE

Application filed March 14, 1929, Serial No. 346,852. Renewed October 9, 1930.

The present invention is concerned with improvements in mechanical parking garages, particularly with garages of the tower or skyscraper type adapted for erection in congested districts and upon relatively small plots of ground.

Primary objects of the invention are to provide a garage of this character in which a maximum amount of space is devoted to storage, a maximum number of cars are parked in the available space, a maximum number of cars may be received and stored in a given period of time, and every car is readily accessible for purposes of expeditious delivery when the owner calls for it.

In carrying out the invention I utilize certain of the principles disclosed in my prior Patent No. 1,636,600 of July 19th, 1927, and certain of the principles disclosed in my co-pending applications Serial No. 295,586, filed July 26th, 1928, and Serial No. 322,330, filed November 28th, 1928. In accordance with the present invention, however, these principles are embodied in a unitary garage structure and are so correlated that a unique garage of maximum capacity and maximum car handling efficiency is produced, and the disadvantages of the previous systems are entirely obviated.

In my prior patent I showed the use of endless connected chains of orbitally movable car parking cabins travelling around a central series of superimposed floors, certain of which serve as storage floors and certain of which serve as car delivery and receiving floors, connected by separate ramps with the street. In this system the "dead" storage space was not utilized with maximum efficiency and whole trains of cabins were tied up for car transportation purposes to and from the dead storage floors.

In application Serial No. 295,586, an improved construction is shown in which the storage floors instead of being fed from the endless cabin chains are fed from the separate elevators and there is provided in effect a pair of interlocking, wholly independent garage systems, one operating on the endless chain principle and the other on the ordinary elevator principle and each system using all

of the available waste space of the other. The storage floors, however, are again substantially "dead" storage space from which cars are removed only with difficulty and in expeditiously.

In application Serial No. 322,330 I disclosed the use of automatic parking equipment in the form of horizontally movable storage platforms on the storage floors. Considerable "dead" storage space still remained, however, and the method of shifting cars from elevators to platforms and of alining the platforms with the elevators was not entirely satisfactory or wholly conducive to rapid car handling.

In accordance with the present invention, the construction is materially improved by retaining the endless vertically disposed parking cabin trains and by the provision of automatic car handling apparatus on the storage floors of a secondary or elevator system. This apparatus is in the nature of a series of connected horizontally movable car parking platforms or trucks conveniently accurately alinable with the elevators for the reception of the incoming and outgoing cars. Thus the need for shuffling the cars on the storage floors when one of the cars is called for is entirely obviated and any car parking platform may be rapidly brought into registry with the delivery elevator at any time.

A feature of the invention is the novel manner in which the platforms of the horizontal trains are mounted. By the simple expedient of disposing these platforms at an angle relatively to the tracks in or on which they travel; a tremendous economy of space is effected particularly when the platforms are swinging around the curved end portions of their orbit. This angular disposition of the platforms also insures their correct registry with the special elevator mechanism which is used for conveying the cars to and from the storage floors, and the arrangement of the platforms and tracks leaves practically no dead storage space in the entire system.

Thus the usual expeditious car handling facilities of any endless chain system are afforded and the cars parked on the horizontally movable platforms may be handled almost

as expeditiously as those in the endless cabin train.

With the above noted and other objects in view, the invention consists in certain novel features of construction and combinations and arrangements of parts which will be more fully hereinafter described and pointed out in the claims.

The invention may be more fully understood from the following description in connection with the accompanying drawing, wherein:

Fig. 1 is a broken sectional plan view of a garage embodying the invention, the right hand portion of this view showing a typical plan of one of the upper car parking floors 15 and the left hand portion of the view showing a typical ground floor plan.

Fig. 2 is a broken vertical sectional view 20 through the garage taken approximately on the line 2—2 of Fig. 1.

Fig. 3 is an enlarged fragmentary plan view of one of the platforms with parts broken away and in section to disclose the actuating means for the platform train.

The drawing is in many respects diagrammatic throughout. Since reference may be had to my prior patent for details of the endless chain structure, to my prior application 25 Ser. No. 295,586 for details of the elevator structure and to my prior application, Serial No. 322,330, for details of the platforms and their actuating means, none of these parts are illustrated in profuse detail here.

In the drawing, I have shown a relatively tall garage building erected upon a relatively narrow lot, say 60 feet, which may be of any depth desired, say 100 to 200 feet. The side walls of the building are shown at 10, 30 the roof at 11 and the basement at 12. At each side of the building but terminating short of the front and rear thereof are banks of vertical shaftways 13, connected at their tops and bottoms by crossways 14 and 15 respectively. The endless chains of car parking cabins 16 are hung between and carried by pairs of endless flexible devices 17 and travel in the orbital paths defined by opposite shaftways 13 and connective crossways 14 and 15. The flexible devices 17 may be actuated by and guided over pairs of drums or sprockets 18 mounted in the upper crossways and guided in any suitable manner (not shown) through the lower crossways.

The central space between the banks of shaftways 13 and between the upper and lower crossways 14 and 15 is horizontally subdivided into a plurality of floors 18, the upper floors of this series serving as storage 40 floors and the lower floors 19 and 20 serving as car delivering and car receiving floors respectively. The floor 19 usually somewhat above street level communicates with the street through one or both ends of the garage 45 by a descending ramp 21 and a ramp 22 from

the street level leads down to the receiving floor 20.

Preferably a central control house 23 is disposed between the ramps. This control house contains automatic electrical control mechanism (which forms no part of the present invention) for automatically setting the endless cabin chains 16 in motion to bring any cabin into position at the receiving or delivery floors 19 and 20.

At the front of the building forwardly of the shaftway banks 13 there are provided a pair of ordinary elevator shaftways 24, one at each side of the building in which elevators 25 are vertically movable. Each elevator 24 mounts a swivelled carriage or car frame 26, which under normal conditions is axially aligned with the elevators, as shown in Fig. 1, so that a car may drive from the street over the roadway 27 and through the doorway 28 directly into one of the elevators or may drive out of the other elevator through the doorway 29 and over the roadway 30 to the street. If desired, and particularly where the garage is of a double ended construction, that is to say, where it fronts on two streets, rear elevator shaftways 24a may be provided between the rear end of the banks of shaftways 13 and the rear of the garage, these shaftways guiding the vertical travel of elevators 25a similar to elevators and carrying similar swinging car frames 26a.

The upper or storage floors 18 of the garage are relatively restricted at their intermediate portions by the banks of shaftways 13 and beyond the ends of said banks are expanded laterally at 18a to an extent limited by the elevator shaftways 24 and 24a.

It is on these floors that the endless series 50 of car parking platforms 31 are provided, these platforms receiving cars from and delivering them to the various elevators 25 and 25a.

The structural details of the platforms themselves, their swivelled supporting trucks 32 and the rods 34 which connect the trucks of adjacent platforms are fully described in my copending application Serial No. 322,330, and have not been illustrated in great detail here. The endless tracks 33 in which the horizontal platform train is guided includes parallel runs disposed as close together as possible between the banks of shaftways. Beyond the shaftway banks 13 the straight 60 parallel runs of the tracks are connected by relatively large loops 33a, these loops being of partial circular shape and of a diameter greater than the distance between the parallel straight runs of the track and as large as permitted by the floor space at 18a.

I have discovered that if the platforms 31 are mounted with their longitudinal axes at an angle of approximately 35° to the tracks on which the platforms travel, a considerably greater number of platforms may be

connected together for travel on an orbital track of a given length and by mounting platforms askew on the track I furthermore bring them automatically into exact alinement with the swinging car carrying frames 26 and 26a of the elevators 25 and 25a. The width of the storage floors 18 is determined by the width of the car roadways or delivery and receiving floors 19, 20. These floors must be about 25 feet in width to permit manipulation of the cars thereon. By disposing platforms 31 at an angle of about 35° to the track the platforms of the two parallel track runs just clear each other and the walls of the shaftways 13.

The elevator shaftways at the upper floors have relatively wide side doorways 35 so that the frames 26 or 26a with a car thereon may be swung laterally partly out of the elevator to the position shown in dotted lines in Fig.

1. That is to say, it may be swung at an angle of approximately 45° to the longitudinal axis of the elevator whereby a car may be driven straight off the frame or turntable 26 on to a waiting platform 31. It will be particularly noted in Fig. 1 that each platform in one portion of its travel around the loop 33a reaches a position of exact alinement with an outwardly swung car-carrying frame 26a, so that a car may be readily driven on to the platform from the frame of either elevator 25a. While not illustrated, a similar condition exists in connection with the elevator frames 26 at the opposite end of the garage where the opposite loop 33a of the track is provided.

Means for actuating the endless horizontal train of platforms may conveniently include the sprocket chain 35 carrying gripper members 36 which engage with the pendant king pins 37 of the platform supporting trucks 32. In order to hold the platforms against lateral tilting their free corners are preferably supported on rollers or casters shown in dotted lines at 37.

It will be understood that the trains of horizontal car parking platforms are also automatically electrically controlled in any suitable manner from the control house 23, so that any platform of any train may be brought automatically into alinement with any elevator.

The operation of the garage is as follows: A car entering the front of the garage may drive down the ramp 22 on to the receiving floor 20 where it is swung to the left and into a waiting storage cabin 16, which has been brought into proper receiving position by manipulation of the central controls.

When cars parked in any of the cabins 16 are called for the operative in charge of the controls sets the required cabin train in motion, bringing the desired cabin into alinement with the delivery floor 19 and the car is driven out on to the delivery floor, swung

to the left, driven down the ramp 21 and leaves the garage, there being no need for the driver to do anything but drive his car into the cabin and drive it out again.

When the endless trains of vertically movable parking cabins 16 are filled, the horizontal trains of platforms 31 are resorted to for car storage purposes, or if desired, the garage may have two different parking rates, one for the cabins 16 and one for the platforms 31, the rate for the latter storage being slightly less due to the fact that the car handling is slightly slower. When a car is to be stored on one of the platforms 31, the driver runs it over the roadway 27 into the elevator 25 and there leaves the car. A garage attendant then runs the elevator 25 up to the desired storage floor 18 and swinging the car carrying frame 26 to the desired angle drives the car off on to a waiting empty platform which has previously been brought into receiving position by manipulation of the controls at the central control house 23. Similarly when a car on one of the floors 18 is required by the owner, the control man shifts the platform carrying this car into registration with the opposite elevator 25, an attendant runs the elevator 25 up to the parking floor, drives the car from the platform on to the frame 26, swings the frame back into the elevator, descends to the ground floor and delivers the car to its owner.

It will thus be seen that the present garage provides a pair of totally independent car parking systems, both fully automatic in operation. The two systems are so mechanically interrelated insofar as the building structure itself is concerned that practically every available foot of parking space is utilized efficiently, all this being accomplished without in any way impeding the expeditious reception of delivery of cars.

The garage combination described above is particularly effective when the cabins of the endless vertical trains are designed for standard sized cars. Undersized and oversized cars may then be stored on the horizontal movable platforms, certain of the platforms being designed for oversize cars and certain of them for undersized cars.

Obviously the arrangement of the vertical trains and the horizontal trains is subject to considerable variation. In many instances the horizontal trains may encircle the vertical trains instead of being encircled by them, or the two sets of trains might be linked together, one run of the horizontal trains lying between the runs of the vertical train and vice versa.

It will thus be seen that there is herein described a device in which the several features of this invention are embodied, and which device in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

10. What I claim is:

1. A pair of mechanically interfitting and functionally independent mechanical car parking systems housed within a single building, one of said systems including spaced banks of vertical shaftways connected at their upper and lower ends by horizontal cross-ways, and endless chains of car storage cabins travelling through the orbital pathways defined by said shaftways and cross-ways, the other of said systems including car storage floors occupying the space between the shaftway banks, elevators independent of the storage cabins for conveying cars thereto, and endless trains of car parking platforms travelling over said floors.

2. A pair of mechanically interfitting and functionally independent mechanical car parking systems housed within a single building, one of said systems including spaced banks of vertical shaftways connected at their upper and lower ends by horizontal cross-ways, and endless chains of car storage cabins travelling through the orbital pathways defined by said shaftways and cross-ways, the other of said systems including car storage floors occupying the space between the shaftway banks, elevators independent of the storage cabins for conveying cars thereto, and endless trains of car parking platforms travelling over said floors, each system including means whereby cars may be loaded on and unloaded from its parking devices and said means being wholly independent of each other.

3. A pair of mechanically interfitting and functionally independent mechanical car parking systems housed within a single building, one of said systems including spaced banks of vertical shaftways connected at their upper and lower ends by horizontal cross-ways, and endless chains of car storage cabins travelling through the orbital pathways defined by said shaftways and cross-ways, the other of said systems including car storage floors occupying the space between the shaftway banks, elevators independent of the storage cabins for conveying cars thereto and endless trains of car parking platforms travelling over said floors, the storage cabin system including a loading floor arranged between the shaftway banks beneath the storage floors of the other system and driveways leading from said floor to the street.

4. A garage building including banks of

vertical shaftways at opposite sides thereof, upper and lower transverse cross-ways connecting pairs of opposite shaftways at their tops and bottoms, storage floors disposed between the banks of shaftways and extending longitudinally therebeyond, an elevator shaftway between the first mentioned banks and an end of the building, a vertically movable conveyor elevator therein adapted to convey cars to and from the end of the storage floors, endless chains of car storage cabins mounted to travel in the orbital pathways defined by the first mentioned shaftways and cross-ways, and horizontally movable endless trains of car parking platforms on the storage floors.

5. A relatively long narrow building of substantial height and a pair of independently operating car storage systems housed therein, one of said systems including endless chains of car storage cabins, shaftways at opposite sides of the building spaced from the ends thereof and horizontal crossways at the top and bottom of the building connecting said shaftways, said shaftways and cross-ways defining an orbital path for the travel of the cabins of the endless chains, the other system including storage floors, the restricted intermediate portions of which are disposed between the banks of shaftways and the ends of which extend the full width of the building, conveyor elevators disposed at the ends of the building beyond the storage cabin shaftways for delivering and receiving cars from the storage floors and endless trains of car parking platforms movable over the storage floors.

6. A relatively long narrow building of substantial height and a pair of independently operating car storage systems housed therein, one of said systems including endless chains of car storage cabins, shaftways at opposite sides of the building spaced from the ends thereof and horizontal cross-ways at the top and bottom of the building connecting said shaftways, said shaftways and cross-ways defining an orbital path for the travel of the cabins of the endless chains, the other system including storage floors, the restricted intermediate portions of which are disposed between the banks of shaftways and the ends of which extend the full width of the building, conveyor elevators disposed at the ends of the building beyond the storage cabin shaftways for delivering and receiving cars from the storage floors, and endless trains of car parking platforms movable over the storage floors, the endless trains of platforms including parallel runs travelling in the restricted space between the shaftway banks and enlarged end loops travelling on the enlarged ends of the floors.

7. A relatively long narrow building of substantial height and a pair of independently operating car storage systems housed

- therein, one of said systems including endless chains of car storage cabins, shaftways at opposite sides of the building spaced from the ends thereof and horizontal cross-ways 5 at the top and bottom of the building connecting said shaftways, said shaftways and crossways defining an orbital path for the travel of the cabins of the endless chains, the other system including storage floors, the 10 restricted intermediate portions of which are disposed between the banks of shaftways and the ends of which extend the full width of the building, conveyor elevators disposed at the ends of the building beyond the storage cabin 15 shaftways for delivering and receiving cars from the storage floors, and endless trains of car parking platforms movable over the storage floors, the endless trains of platforms including parallel runs travelling in the restricted space between the shaftway banks 20 and enlarged end loops travelling on the enlarged ends of the floors, the platforms in certain portions of their travel around the loops alining with the elevators.
- 25 8. A relatively long narrow building of substantial height and a pair of independently operating car storage systems housed therein, one of said systems including endless chains of car storage cabins, shaftways at opposite sides of the building spaced from the ends thereof and horizontal cross-ways at the top and bottom of the building connecting said shaftways, said shaftways and crossways defining an orbital path for the travel of the cabins of the endless chains, the other system including storage floors, the restricted 30 intermediate portions of which are disposed between the banks of shaftways and the ends of which extend the full width of the building, conveyor elevators disposed at the ends of the building beyond the storage cabin shaftways for delivering and receiving cars from the storage floors, and endless trains of car parking platforms movable over the storage floors, the endless trains of platforms including parallel runs travelling in the restricted space between the shaftway banks and enlarged end loops travelling on the enlarged ends of the floors, the platforms in certain portions of their travel around the loops alining with the elevators.
- 35 9. A garage including a storage floor, an endless track on the floor including straight runs and curved runs and an endless connected series of car parking platforms movable along the track and having their longitudinal axes disposed at an angle to the straight portions of the track.
- 40 10. In a garage a plurality of superimposed storage floors, an elevator shaftway having doors communicating therewith, an endless series of low, connected car parking plat-
- 45 forms movable over the floors, an elevator in the shaftway, a car carrying track unit swivelly mounted near one end on the floor of the elevator and capable of swivelling movement partially out of the elevator to bring a car which it carries into alinement with one of the platforms when the latter is in a predetermined position.
- 50 11. In a garage a plurality of superimposed storage floors, an elevator shaftway having doors communicating therewith, an endless series of low connected car parking platforms movable over the floors, an elevator in the shaftway, a car carrying track unit swivelly mounted near one end on the floor of the elevator and capable of swivelling movement partially out of the elevator to bring a car which it carries into alinement with one of the platforms when the latter is in a predetermined position, the longitudinal axes of said platforms being disposed at an angle relatively to the line of travel of the platforms.
- 55 12. In a garage a connected series of car parking elements movable in an orbit the plane of which is vertical and endless series of car parking devices movable in an orbit the plane of which is horizontal, one of said trains encircling the other.
- 60 13. In a garage a connected series of car parking elements movable in an orbit the plane of which is vertical, and endless series of car parking devices movable in an orbit the plane of which is horizontal, one of said trains encircling at least one run of the other train.
- 65 14. In a garage a connected series of car parking elements movable in an orbit the plane of which is vertical, and endless series of car parking devices movable in an orbit the plane of which is horizontal, the horizontal train being encircled by the vertical train.
- 70 15. In a garage, a series of endless car parking trains moving in spaced vertical shaftways, horizontal storage floors between the shaftways, endless trains of car parking platforms travelling on the floors and independent means for bringing cars to and from the parking platforms.
- 75 16. In a garage, a plurality of superimposed storage floors, endless series of car parking platforms movable over the floors, an elevator shaftway, an elevator running in the shaftway, a movable track carried by the elevator and shiftable into alignment with the platforms when the latter are in a predetermined position.
- 80 17. In a garage, a plurality of superimposed storage floors, endless series of guided car parking platforms movable over the floors, the longitudinal axes of said platforms being disposed at an angle relatively to the line of travel of the platforms, and means for transferring cars to or from any of the parking platforms on any of the storage floors.

18. In a garage, a plurality of superimposed storage floors, endless series of guided parking platforms movable over the floors, the longitudinal axes of said platforms being disposed at an angle to the line of travel of the platforms, an elevator shaft, an elevator running in the shaftway, a track on the elevator movable into alignment with any of the platforms when the latter are in a predetermined position.

Signed at New York, in the county of New York and State of New York, this 12th day of March, A. D. 1929.
